UNITED STATES PATENT OFFICE.

STEPHEN A. DAVIS, OF NEWARK, NEW JERSEY, ASSIGNOR TO DOMESTIC SEWING MACHINE COMPANY, OF NEWARK, NEW JERSEY, A CORPORATION OF NEW JERSEY.

DROP-HEAD SEWING-MACHINE.

962,700.

Specification of Letters Patent. Patented June 28, 1910.

Application filed October 19, 1907. Serial No. 398,158.

To all whom it may concern:

Be it known that I, STEPHEN A. DAVIS, a citizen of the United States, and a resident of Newark, in the county of Essex and State 5 of New Jersey, have invented certain new and useful Improvements in Drop-Head Sewing-Machines, of which the following is a description.

My invention is an improvement in drop- 10 head sewing machines and relates particularly to an improved means for raising and lowering the sewing head.

My invention has for its object the improvement of sewing machines of the type 15 patented to myself and A. S. Wass in United States Patent No. 540,823, granted June 11, 1895. I find that in machines made with the wooden guide rods shown in the above mentioned patent, there is considerable tend- 20 ency for such guide rods to shrink, warp and swell, according to the varying conditions of the weather, and thus interfere with the smooth operation of the device. In my improved machine these guide rods are made 25 of metal and the objections which have heretofore been presented are thereby obviated. In addition to this change I have made a number of other improvements in this type 30 of machine as will hereinafter appear, and have greatly simplified and improved the same.

With these and related objects in view my invention consists of the parts, improvements and combinations hereinafter set 35 forth and claimed.

In the accompanying drawings, forming a part of this specification, wherein the same reference numerals are uniformly applied to the same parts, Figure 1 is a sectional front 40 elevation of a drop-head sewing machine embodying the preferred form of my invention, the cabinet being shown in section; Fig. 2 is a view similar to Fig. 1 showing the sewing head lowered into the cabinet, 45 and Fig. 3 is a sectional detail view taken at right angles to Fig. 2, the sewing head being removed.

1 represents the cabinet of the machine provided with the usual legs 2, driving wheel 50 3 and sewing head 4. The devices for raising and lowering the head are situated within the cabinet, near the back thereof, and for the principal part are supported

upon the back plate 5 of the cabinet. As heretofore, the cover 6 is made use of as a 55 lever for operating these devices. The sewing head is provided with a base plate 7 and secured beneath this base plate, preferably by machine screws 8, is a frame 9 which is conveniently made of a single casting. The 60 frame 9 is provided with downwardly extending legs 10 which are offset at their lower ends as shown at 11, and provided with openings to receive the guide rods 12. The frame is also provided with backwardly ex- 65 tending lugs 13 near its upper portion which are likewise perforated for the passage of the guide rods 12. These guide rods are set parallel to one another in the machine and are secured at their upper ends by means of 70 holding plates 14 to the top plate 15 of the cabinet. At their lower ends these guide rods 12 are secured to the back plate by means of holding members 16. The guide rods, as is usual in this type of machine, are 75 not placed quite vertically in the machine, but stand at a slight angle so that as the head is lowered within the machine it will be guided to one side and away from the driving wheel 3.

The hinged cover plate 6 is provided with a slot 17 in which is received the link 18 pivoted to the cover plate at 19. This link also lies, as shown in Figs. 1 and 3, in the slot 20 in the back part of the top 85 piece of the cabinet. The said link has an offset portion 21 extending downwardly into the machine and at the end of this offset portion the link 18 is pivotally secured at 22 to one arm 23 of a bell crank which 90 comprises also the arm 24 which may be pivotally adjusted with respect to the arm 23, by means of set screws 25. This bell crank is pivoted to the back plate of the cabinet at 26. A link 27 is pivoted at its 95 ends to the arm 24 and the frame 9 respectively. A spring 28 is secured at one end to the top plate of the cabinet and at its other end to the arm 24 of the bell crank, substantially midway between the ends 100 thereof.

To operate the parts thus far described, when, for example, they are in the position shown in Fig. 2, the hinged cover 6 is lifted by the hand of the operator and 105 turned back into the position shown in Fig.

1. This motion of the cover through the link 21 operates to turn the bell crank 23, 24 upon its pivot 26 and the frame 9 is pushed upwardly upon the guide rods 12, 5 and the sewing machine head and base plate 7 raised into the position shown in Fig. 1 in which position the parts are locked by reason of the pivot 19, of the link 18 being lower than the hinge of the cover 6. The 10 spring 28 of course assists in maintaining the sewing head and its base plate in the raised position. If it be found that the base plate is either too high or too low, its position may be adjusted by means of the 15 set screws 25 acting through the arm 24 and the link 27.

When the sewing head and its connected parts are in the lowered position within the cabinet, it is desirable that means be 20 provided for holding the parts rigidly with respect to one another, so that, for instance, when the machine is being shipped or moved from place to place, the parts will not be racked and shaken. To this end I provide 25 means between the front of the cabinet and the base plate of the sewing head, which operates to resiliently press the base plate toward the rear of the cabinet and thus maintain the parts rigidly in place. The 30 preferred means used for this purpose comprises a leaf spring 29 secured to the upper and lower portions of the front piece or door 30 of the cabinet. This leaf spring may be made to operate more effectively by 35 giving it a reverse bend 31 at its lower end before it is secured at that end to the cabinet. A metallic rubbing piece 32 is preferably secured to the front of the base plate 7 where it rests against the spring 29. 40 One or more of these springs 29 and metallic pieces 32 may be provided as desired. It will be evident that, when the base plate carrying the sewing head is lowered within the cabinet, the parts will be rigidly maintained in place by means of the spring 29 45 so that all tendency to shaking and racking will be obviated, and by this means also the sewing head will be locked in its depressed position by means of the frictional engagement between the parts 29 and 32.

Having now described my invention, what I claim is:

1. In a drop-head sewing machine, the combination of a base plate and sewing 55 head, means for raising and lowering the same, and means interposed between the front of the cabinet and the base plate for pressing the same backward toward the rear of the cabinet, substantially as set forth.

2. In a drop-head sewing machine, the combination with the cabinet, of a sewing head and its base plate, means for raising and lowering the sewing head and means 60 operating by friction to retain the sewing

head in its lowered position, substantially as set forth.

3. In a drop-head sewing machine, the combination with the cabinet, of the sewing head, a spring connected to the sewing head 70 and tending to elevate it and means operating by friction to retain the sewing head in its lowered position, substantially as set forth.

4. In a drop head sewing machine, the 75 combination with the cabinet, of a sewing head movable up and down and a leaf spring interposed between the front of the cabinet and the sewing head, substantially as set forth.

5. In a drop head sewing machine, the combination with the cabinet, of the sewing head and its base plate movable up and down in the said cabinet, a leaf spring secured to the front of the cabinet and pressing 85 against the said base plate, and a metallic rubbing piece secured to the base plate, substantially as set forth.

6. In a drop head sewing machine, the combination with the cabinet, of a sewing 90 head and its base plate movable up and down therein and a leaf spring secured to the front of the cabinet at its upper portion and extending downwardly to the lower portion thereof and therat provided with a 95 reverse bend and secured to the lower portion of the said front plate, the lower portion of said spring being positioned to press against the said base plate when the latter is in lowered position, substantially as set 100 forth.

7. In a drop head sewing machine, the combination with the cabinet, of a lid hinged thereto and provided with a slot therein, a pair of inclined metallic guide rods secured 105 within the cabinet at the rear thereof, a sewing head movable up and down on the said guide rods, a bell crank lever pivoted to the cabinet and having the arms thereof adjustable relative to one another, means of connection between one of the arms of said bell crank lever and the sewing head, a contraction spring secured to the cabinet and to one of the arms of the bell crank lever and a link pivoted at one end to the hinged lid and 110 connected at its other end directly to one of the arms of said bell crank lever, and adapted to fit the slot in the lid, substantially as set forth.

8. In a drop head sewing machine, the 115 combination with the cabinet, of a lid hinged thereto and provided with a slot therein, a pair of inclined metallic guide rods secured within the cabinet at the rear thereof, a sewing head movable up and down on the said 120 guide rods, a bell crank lever pivoted to the cabinet and having the arms thereof adjustable relative to one another, means of connection between one of the arms of said bell crank lever and the sewing head, a con- 125

130

traction spring secured to the cabinet and to one of the arms of the bell crank lever and a link having a substantially straight upper surface and pivoted at one end to the hinged lid and provided near its other end with a downwardly extending portion, the lower part of the downwardly extending portion of the said link being pivoted to one of the arms of said bell crank lever, and the said

link being adapted to fit the slot in the lid, 10 substantially as set forth.

This specification signed and witnessed this 17th day of October 1907.

STEPHEN A. DAVIS.
